UNITED STATES PATENT OFFICE.

JOSEPH M. REAMS, OF GRAMPIAN, PENNSYLVANIA.

CHAIN WRENCH.

SPECIFICATION forming part of Letters Patent No. 768,146, dated August 23, 1904.

Application filed January 21, 1904. Serial No. 190,005. (No model.)

To all whom it may concern:

Be it known that I, JOSEPH M. REAMS, a citizen of the United States, residing at Gram-
5 pian, in the county of Clearfield and State of
Pennsylvania, have invented certain new and
useful Improvements in Chain Wrenches; and
I do hereby declare the following to be a full,
clear, and exact description of the invention,
such as will enable others skilled in the art to
10 which it appertains to make and use the same.

My present invention relates to improve-
ments in the class of chain wrenches; and its
novelty lies particularly in the endless-chain
construction in combination with means for
15 adjusting the same to fit different-size socket
portions and means for locking the several
parts of the device whereby motion may be
imparted to the socket portion in one direc-
tion.

20 In order that my invention may be thor-
oughly understood, I have clearly and fully
described and illustrated the same in the an-
nexed specification and drawings, in which—

Figure 1 is a side view of my improved de-
25 vice. Fig. 2 is a view similar to Fig. 1, but
with a portion of the case removed. Fig. 3
is an edge view of my device. Fig. 4 is a
longitudinal section of Fig. 3 with a portion
of the handle shown in elevation.

30 In the several views like letters of refer-
ence designate similar parts of my device.
A in the drawings represents the case of
my improved wrench, preferably constructed
35 in one piece and provided with a handle B,
which may be integral therewith, as shown,
or secured thereto in any desired manner.
Said case comprises a forked portion $a a'$, be-
ing the extending portions thereof, said ex-
40 tending portions being provided with longi-
tudinally-extending slots C C', respectively.
D is a U-shaped slide adapted to be adjusted
in said slots C C' in said case A. A' is a
socket in said case A, adapted to receive the
45 threaded projection d of said slide D, said
projection being provided with an adjusting-
nut E, whereby said slide D may be adjusted
in said slots C C' by turning said nut E. F is
a roller mounted in said U-shaped slide upon
50 a removable pin f . G is an inclined projec-
tion, preferably removably mounted in the

end of said case and is provided with suitable
teeth. H is a socket portion of any desired
form and is adapted to be retained adjacent
to the end of said case by an endless chain J,
adapted to pass over said roller F in said slide 55
D. I is a suitable roller mounted in the end
of said case upon a removable pin i to permit
said case to revolve around said socket por-
tion.

In the drawings I have illustrated my pre- 6c
ferred form of chain as composed of slightly-
curved links comprised alternately of three
and four sections provided on both edges
with suitable teeth; but it should be clearly
understood that I may employ various forms 65
of chains without departing from the spirit
of my invention. In the form of chain shown
it will be noted that the teeth on the outer
side thereof are oppositely disposed to those
on the inner side and are adapted to engage 70
teeth on a clutch d' , located in said U-shaped
slide D, to prevent said case from slipping on
said chain in but one direction, said clutch be-
ing provided with a spring d'' , adapted to nor-
mally hold it in engagement with said chain. 75

From the foregoing description the opera-
tion of my device is obvious and as follows:
A socket portion H, adapted to fit the object
to be rotated, having been placed with said
endless chain, the same is tightened through 80
the medium of the roller F in said adjustable
slide D to retain said socket portion against
said roller in the end of said case. The socket
portion is then fitted to the object to be ro-
tated, and the handle on said case is moved in 85
the direction of the inclined projection G on
said case, thus forcing the same against said
socket portion and also forcing the teeth on
the inside of said chain against said socket
portion. The clutch in said U-shaped pro- 90
jection simultaneously engaging with said
chain it is apparent the continued movement
of said handle will impart motion to said
socket portion, thereby turning the nut or
other object; but when the movement of said 95
handle is reversed said projection G on said
case will be thrown out of engagement with
said socket portion and the clutch d' in said
case will slip over said chain, whereby it is
apparent that as the movement of the handle 100

is continued in this direction the case will slide on said chain, thereby permitting the socket portion to remain stationary until the movement of the handle is again reversed to take a new grip.

Although I have described and illustrated my device as used in connection with a socket portion, it should be understood that by removing said socket portion said chain may be 10 placed around a pipe or other object if it is desirable to use the device in this manner, the operation being the same as already described.

What I claim, and desire to secure by Letters Patent, is—

- 15 1. In a wrench of the class described, the combination with a case provided with a handle, of a socket portion, an endless chain passing through said case and adapted to retain said socket portion adjacent to the end of said case and means for locking said case chain and socket portion whereby movement of said handle will impart motion to said socket portion in one direction, substantially as and for the purpose described.
- 20 2. In a wrench of the class described, the combination with a case provided with a handle, of a roller adjustably mounted in said case, an endless chain passing over said roller and having a portion exterior to said case, a socket portion within said exterior portion of said chain and adjacent to the end of said case, means for adjusting said roller to tighten said chain on said socket portion and means for locking said case chain and socket portion 30 whereby movement of said handle will impart motion to said socket portion in one direction, substantially as and for the purpose described.
- 25 3. In a wrench of the class described, the combination with a case provided with a handle, of a socket portion, an endless chain passing through said case and adapted to retain said socket portion adjacent to the end of said case, a projection on said case adapted to engage said socket portion to prevent said case from slipping thereon and a clutch in said case adapted to engage said chain to prevent said case from sliding thereon in but one direction whereby movement of said handle will 35
- 40 45

impart motion to said socket portion in one direction, substantially as and for the purpose 50 described.

4. In a wrench of the class described, the combination with a case provided with a handle, of a roller adjustably mounted in said case, an endless chain passing over said roller and having a portion exterior to said case, a socket portion within said exterior portion of said chain and adjacent to the end of said case, means for adjusting said roller to tighten said chain on said socket portion, a projection on 55 said case adapted to engage with said socket portion to prevent said case from slipping thereon, and a clutch in said case adapted to engage with said chain to prevent said case from sliding thereon in but one direction, whereby 60 movement of said handle will impart motion to said socket portion in one direction, substantially as and for the purpose described.

5. In a wrench of the class described, the combination with a case provided with a handle, of a roller adjustably mounted in said case, an endless chain passing over said roller and having a portion exterior to said case, said chain being provided on both sides with clutching-teeth, a socket portion within said exterior portion of said chain and adjacent to the end of said case, means for adjusting said roller to tighten said chain on said socket portion, a roller in the end of said case adapted to bear against said socket portion, an inclined 70 projection on said case adapted to engage with said socket portion to prevent said case from slipping thereon and a clutch in said case adapted to engage with said chain to prevent said case from sliding in but one direction, whereby 75 movement of said handle on said case will impart motion to said socket portion in one direction, substantially as and for the purpose described.

In testimony whereof I affix my signature in 80 the presence of two witnesses.

JOSEPH M. REAMS.
